UNITED STATES PATENT OFFICE.

MEYER J. GOLDBERG, OF MUSKEGON, MICHIGAN, ASSIGNOR, BY MESNE ASSIGNMENTS, TO THE MAXIMOTOR COMPANY, OF MUSKEGON HEIGHTS, MICHIGAN, A CORPORATION OF MICHIGAN.

GASOLINE ENGINE.

Application filed April 2, 1920. Serial No. 370,843.

To all whom it may concern:

Be it known that I, MEYER J. GOLDBERG, formerly a subject of the Czar of Russia, but who have declared my intention of becoming a citizen of the United States, and have taken out my first naturalization papers, and residing at Muskegon, county of Muskegon, State of Michigan, have made a certain new and useful Invention in Gasoline Engines, of which the following is a specification.

This invention relates to gasoline engines.

The object of the invention is to provide a structure of gasoline engine which is exceedingly simple, economical to manufacture and easy to assemble, and which is efficient in operation.

A further object is to provide a gasoline engine of small size, of few parts and low cost, which is strong, rugged and sturdy and well adapted for general use.

A further object is to provide an engine of the nature referred to wherein all the working parts, including the fly wheel are housed within the casing of the machine.

A further object is to provide an engine structure composed of various assemblages of parts constituting units which are capable of quick and easy assembly into the complete machine.

Other objects of the invention will appear more fully hereinafter.

The invention consists substantially in the construction, combination, location and relative arrangement of parts, all as will be more fully hereinafter set forth, as shown in the accompanying drawings, and finally pointed out in the appended claims.

In the drawings:—

Fig. 1 is a view in side elevation of a gasoline engine constructed in accordance with the principles of my invention.

Fig. 2 is a front end elevation of the same.

Fig. 3 is a view in central vertical longitudinal section on the line 3, 3, Fig. 2, looking in the direction of the arrows.

Fig. 4 is a view in transverse section through the crank shaft bearings on the line 4, 4, Fig. 3.

Fig. 5 is a view in vertical transverse section through the cylinder head, the intake and exhaust valves and the fuel control valve, on the line 5, 5, Fig. 1.

Fig. 6 is a broken detail view in central longitudinal section of the fuel supply and air intake nozzle, and the mixing chamber and balanced throttle valve.

Fig. 7 is a view in end elevation of the air intake nozzle.

Fig. 8 is a broken detail view in side elevation, parts in section on the line 8, 8, Fig. 9, showing the governor mechanism and the gearing arrangement for operating the same.

Fig. 9 is a similar view on the line 9, 9, Fig. 8.

The same part is designated by the same reference numeral wherever it occurs throughout the several views.

In recent years a large demand has developed for gasoline engines of comparatively small size and small power, for general use on farms and in homes for driving various farm and home machinery. Engines of this type and character are frequently required for use in the open where they are unprotected from rain or moisture, and, moreover, they are required to be of such structure as to be capable of operation by the unskilled labor ordinarily encountered in farm and home work. The initial cost as well as the upkeep and safety of operation of engines for such purposes are important factors to be considered in designing a structure to meet the requirements.

It is among the special purposes of my present invention to provide a gasoline engine of comparatively small size and power, which is simple in structure and economical to manufacture, which contains few parts which can be readily removed and replaced when necessary, wherein the working parts are housed within an enclosing casing, thereby protecting them from the effects of rain or moisture as well as protecting the operator or attendant from the danger of injury or accident, and which is strong, sturdy and durable.

In carrying out my invention I provide an enclosing casing 10, which is cast or otherwise formed, in one single piece to include the chamber 11 in which is received the crank-shaft, the magneto, the governor, and its operating gearing, and the fly wheel. The cylinder 12 is cast or formed integrally with the casing 10. The part 13 of the casing which forms one side wall of the

chamber 11 is formed in one with the casing, while the opposite side wall of said chamber is open, as indicated at 14, Fig. 4. A bearing 15, is formed centrally through the integral casing wall 13, in which one end of the crank shaft 16 is received and journaled. If desired this bearing may be bushed, as shown at 17, and lubricated in any suitable or convenient manner, as, for example, by means of the lubricating cup 18. The outer end of the crank shaft extends beyond the wall 13 of the casing and receives thereon a pulley or other form of gear 19 by or through which the power of the engine 15 may be transmitted for use. The fly wheel 20 is arranged within the chamber 11 of the casing and is mounted upon and connected to the crank shaft in any suitable or convenient manner. The other end of the crank shaft 20 is received through and journaled in a bearing 21, formed in a bearing ring 22, arranged to be applied and removably bolted to the casing at the open side 14 of the latter. If desired, this bearing 21 is bushed, as indicated at 23. A cap member 24 is removably bolted to the outer face of the bearing ring 22, and forms a closure for the opening 14 of the casing. The cap member 24, is formed with an opening 25, there-through, which is disposed in line with the end of the crank shaft to permit the insertion of a starting crank to engage the crank shaft end in starting up the engine. A hinged cover plate 26 serves to close the opening 25 in the cap member 24. The upper surface 39 of the bearing 21 in the bearing ring 22 is planed off and forms a seat for the base of the magneto 27. The bearing ring 22 is formed with a bearing 28, within which is mounted a stub 29 upon which is mounted a rotatable gear wheel 30. This gear wheel is formed with a cam 31, on one face of the hub thereof for operating the exhaust valve 45 actuating lever presently to be described, and therefore I will refer to said gear wheel 30, as the cam gear. A pinion 32 is mounted on the crank shaft 16, and this pinion meshes with and drives the pinion 33 of the magneto, and also the cam gear 30. In order to lubricate the bearing 21 in which the crank shaft 16 is journaled, and also the bearing of the cam gear, the bearing ring 22 is formed with a duct 34, which 55 communicates with said bearings, and an oil or grease cup 35 is disposed in communication with said duct.

For access to the chamber 11 for inspection or other purpose, the casing 10 is formed with an opening which is closed by a removable cover 36, in the upper wall of the casing. This cover is provided with a handle or grip 37 which is rotatable thereon and to which, at the inner side of the cover, 60 are connected locking arms 38, which when

said grip is rotated, engage beneath or may be released from the side edges of the opening in the casing.

I will now describe the governor mechanism by which the supply of explosive mixture to the cylinder is controlled. 70

The bearing ring 22 is formed with a bearing 40, see Fig. 9, in which is journaled the governor spindle 41. Upon this spindle is mounted the pinion 41', arranged to mesh with and to be driven by the cam gear 30. Clamped upon or otherwise secured to or formed on to rotate with the spindle 41 are brackets 42, upon which are pivotally mounted the weighted governor arms 43. 80 These weighted arms are rocked upon their pivots to a greater or less extent by centrifugal action according to the speed of rotation of the spindle 41. The spindle 41 is bored or formed hollow and a plunger 44 works in said bore against the action of a spring 45, positioned in said bore. The plunger 44 is provided with a collar 46 which forms a yielding stop or abutment for the light ends of the governor arms 43. 90 The supporting brackets members 42 form a stop for the weighted ends of the governor arms. The bearing ring 22 is formed with a bearing 47 in which is mounted a stud or pin 48. Upon this stud a sleeve 49 is mounted to rock said sleeve, having arms 50, 51, and constituting in effect a double armed lever. To the arm 50 is pivotally connected one end of the throttle valve reach rod 52. The other arm 51, of sleeve 49, is cupped at its free end and receives there-through the hardened pin 53, arranged to take the bearing thereagainst of a pin or projection 54, carried by, or forming an extension of the plunger 44. A spring 55 is interposed between the lever arm 51, and an adjusting screw 56 working in a threaded opening formed through the cap plate 24.

From this description it will be seen that the lever arm 51 is subjected to the opposing tensions of springs 45 and 55, the tension of the latter being adjustable by the adjusting screw 56. The tension of spring 45 exceeds that of spring 55, and consequently the lever arm 51 is held normally in the outer limit of its rocking movement when the engine is at rest, and hence the arm 50 and the reach rod 52 are held in their extreme limits in one direction of movement thereof. 110 This limit corresponds to the position of widest opening of the throttle valve presently to be more fully described. As the engine starts up and its speed increases, centrifugal force will cause the weighted ends of the govenor arms to rock outwardly, thereby causing their light ends to engage the collar 46 on plunger 44, and force said collar into the bore of the spindle 41, against the action of spring 45. The 120 125 130

centrifugal force exerted upon the plunger 44 through the governor arms is augmented by the tension of the lighter spring 55. The result is that lever arm 51 is rocked inwardly, thereby rocking sleeve 49 and lever arm 50, and hence causing the reach rod 52 to move outwardly to cause the throttle valve to move towards closed position. I thus provide an exceedingly simple and sturdy 10 governor mechanism which is composed of few parts inexpensive to manufacture and capable of being easily and readily assembled, or replaced when required, while at the same time I secure an adjustable sensitivity 15 of governor action which responds quickly and accurately to speed variations, thereby securing great smoothness and steadiness of the engine when in operation. It will be understood, of course, that while 20 I have shown and described a specific structure of governor mechanism, and while I have found that structure to be entirely satisfactory in use, I do not wish to be limited or restricted, in the broadest scope 25 of my invention, to the exact details shown and described.

I will now describe the cylinder head and the parts associated therewith, it being understood, of course, that the structure shown 30 is illustrative of a simple practical operative embodiment of my invention.

The cylinder head 57 is removably secured in any suitable manner to the end of the casing 10, and in line with the cylinder 12, as, for example, by means of the clamp bolts 58, and it is formed with a boss 59 for an explosive mixture supply connection 60, and with a boss 61 for an exhaust connection 62. The head 57 is also formed with a passage 63 which communicates through the boss 59 with the intake connection 60. In the passage 63, is received the intake valve cage and assembly. This valve assembly, in the illustrative arrangement shown, consists of 45 a flanged cage 64, the flange 65 of which is secured to the cylinder head in any suitable manner, as, for example, by the securing bolts 66. The cage 64 carries a seat ring 67 at its inner end which seats against a shoulder formed in the cylinder head opening or 50 passage 63. This ring also forms a seat for the inlet valve 68. The stem 69 of this valve works through a bearing therefor formed in the body of the cage 64. A coiled spring 70 interposed between the stem bearing in the 55 cage body and a washer 71 fixed to the valve stem serves to normally maintain this valve yieldingly closed upon its seat. The washer 71 is shown secured to the valve stem by 60 means of a pin 72, and in order to form a housing for said pin, as well as a boss around which the end of the spring 70 engages, the central portion of the washer 77 is depressed, as shown at 73.

65 The cylinder head is also formed with a

passage 74 which communicates through boss 61 with the exhaust connection 62. This passage 74 is controlled by the exhaust valve 75, the stem 76 of which works through a bearing 77 formed in the head. A coiled 70 spring 78 interposed between said bearing 77, and a cupped or centrally depressed washer 79, serves to normally maintain the exhaust valve seated to close the exhaust passage. The washer 79 secured to 75 the exhaust valve stem by means of a pin 80, the central depressed portion of the washer forming a housing for said pin as well as a boss around which the end of the spring 78 engages.

The cylinder head is also formed with an opening 81, therethrough which is preferably located closely adjacent to the inlet valve, and in which opening is inserted the spark plug 82. By thus locating the spark 85 plug in close proximity to the inlet valve, the incoming jets of gaseous mixture which are comparatively cool, serve to maintain the spark plug cool and also to prevent the accumulation of carbon or other deposits 90 thereon.

The cylinder head is formed with an enlarged chamber 83, centrally therein, which is in line with and opens directly into the cylinder 12. This chamber constitutes the 95 compression and ignition chamber, the spark plug projecting into said chamber and the valve controlled intake and exhaust passages also opening directly into said chamber.

The intake valve is periodically unseated, in the illustrated example of my invention, by the suction action of the piston. The exhaust valve, however, is mechanically actuated periodically to open position in proper timed relation after each explosion to permit the escape of the spent gases and other products of combustion from the cylinder. Since the cylinder head with its inlet and exhaust valves, spark plug and intake and exhaust bosses and passages constitute, as 100 an assemblage, a single unit capable, as a unit, of being bolted on or removed from the casing, it is exceedingly desirable to permit the removal of the head from the casing or its application thereto without disturbing or disarranging the exhaust valve operating devices, or the gear or timing arrangement thereof. To accomplish this desirable result I cast or form integrally with the casing 10, suitable lugs 84, between which 105 extends a rock lever 85, said lever being pivotally mounted upon a pivot pin 86, passing through said lever and lugs. One end of this lever extends through an opening 87 into chamber 11 of the casing and 110 carries a roller 88, which bears or works against the cam 31 on the cam gear 30. The outer end 89 of this lever is formed into an open sided cup which receives and acts upon the stem 76 of the exhaust valve. 115 120 125 130

An adjustable set screw 90 serves to regulate the clearance between said lever and valve stem. A spring 91, interposed between the lever 85 and the bottom of the 5 casing serves to maintain the roller 88 against the cam 31, and also a desirable clearance between the said lever and the exhaust valve stem. This structure permits the removal and replacement of the cylinder 10 head without disturbing the exhaust valve operating lever and hence without disarranging the timing of the operations.

If desired, and in order to exclude dust and dirt from the inlet valve assembly, and 15 at the same time present a neat and finished appearance, a cap 92 may be applied over the outer end of the valve cage.

The gasoline or other fuel supply is carried in a reservoir or tank 93, which may 20 be located in any convenient position. In the arrangement shown the tank 93 is positioned between side members or skids 94, which constitute a convenient supporting base upon and to which the engine casing is 25 bolted. These skids may conveniently be of wood, and, in practice, I prefer to support the tank or reservoir 93 above the lower surfaces of said skids in order to remove possibility of puncture of the reservoir, or 30 unevenness of the base setting for the engine, by reason of the bottom of the reservoir coming in contact with a sharp stone or other object.

From the tank leads a supply pipe connection 95, which delivers into a mixing nozzle 96, through an opening 97, which is controlled by a needle valve 98, which is threaded through the wall of the nozzle 96 opposite said opening. The opening 97 is 35 transversely disposed with reference to the length of the nozzle. The outer end of the nozzle is flared or enlarged, as at 99, and is open to the outer air except for an outwardly seating plate or disk valve 100 which is 40 lightly held seated or closed upon an annular rim 101 by means of a spring 102 interposed between said plate or disk and a nut 103 on the end of a rod on which the disk or plate is mounted and which rod is carried 45 by a cross member 104 of the rim 101.

The nozzle 96 communicates through the connection 60 with the intake passage through the boss 59 of the cylinder head. This communication is controlled by means 55 of a special construction of throttle valve 105, which, in this illustrative form of my invention, is of cylindrical shape and works like a piston in a tubular portion of the nozzle 96. The reach rod 52 is connected to the piston valve 105. The outer end of the piston valve is formed with a V-shaped notch 106, the widest portion of which is presented outwards towards the enlarged open 60 end of the nozzle and away from the connection 60.

The engine piston 107, works in the cylinder 12, and the connecting rod 121 is pivotally connected thereto as at 108, and to the crank 109 of the main crank shaft.

It is desirable to efficiently lubricate the 70 piston and also the pivotal connection of the connecting rod and piston. A simple arrangement for this purpose is shown wherein lubricating oil is supplied from a cup 110, through a pipe connection 111, which 75 delivers the lubricant to the inner wall of the cylinder through the hole 112. As the piston works back and forth in the cylinder it wipes the lubricant from the opening 112 and applies and distributes it to and upon the interior wall of the cylinder. In this manner lubricant is carried to a short tube 113 which extends through the wall of the piston over the pivotal connection 108 and directs and insures the dripping of the lubricant into a cup 114, forming part of or 80 communicating with the pivotal connection 108.

The casing 10 is formed with an enlarged 85 chamber 115 to receive a supply of water or other cooling medium. This chamber surrounds the cylinder 12, and also communicates through passages 116, with passages 117 cored or otherwise formed in the head 57, thus constituting a simple but efficient 90 jacket for both the cylinder and the head. The heat of the head creates a circulation of the cooling water, thereby insuring a most efficient heat radiation whereby the engine 95 in operation is maintained remarkably cool. The casing 10 is formed with an opening in the top thereof through which the circulating water may be introduced into chamber 115. The mouth of this opening is outwardly flared as shown at 118, to facilitate the 100 operation of supplying the circulating water to the chamber 115 without spilling the same over the interior of the casing.

A drain hole from the chamber 115 may be 105 provided through the bottom wall of the casing, as indicated at 119, and likewise a drain hole from the crank chamber may be provided through the casing wall as indicated at 120.

From the foregoing description it will be 115 seen that I provide an exceedingly simple and efficient engine which is strong and durable, economical to manufacture, and the parts of which are few and easily and readily assembled. All working parts, including the fly wheel, as well as the magneto, are 120 inclosed or housed within the casing, thereby protecting the gearing and other working parts from dust or dirt, while removing danger of accident or injury to attendants by getting caught in the working parts of the engine. By thus enclosing the magneto within the casing it, as well as the other parts inclosed in the casing, are protected 125 from the effects of rain or moisture even if 130

the engine is operated out in the open. Besides a very neat and attractive appearance is given to the entire engine by reason of the concealment from view of its working parts, 5 and by the plain symmetrical outline of the casing.

It will also be observed that I provide a structure wherein a large heat radiation is secured, thereby enabling me to maintain 10 the engine remarkably cool while in operation.

The governor mechanism which I have described enables me to secure an exceedingly steady operation of the engine, and since 15 the throttle valve which the governor mechanism operates or controls is a balanced piston valve it will be readily seen that the work required of the governor mechanism is exceedingly slight and hence these parts are 20 very durable.

By reason of the open side cup shape of the end of the exhaust valve operating lever the entire cylinder head may be removed from and reapplied to the cylinder without 25 disturbing or disarranging said lever, its mounting or the appliances for operating it.

In assembling the engine, the crank shaft with the fly wheel 20 and gear 32 mounted thereon, forms a unit. This unit is then 30 passed through the opening 14 in the side of the casing, and the end of the crank shaft is inserted through the bearing 15 in the wall or closed side of the casing. The bearing ring, with the magneto 27 attached to the 35 seating 39, the cam gear 30 and its supporting stud 29; and the governor structure including the spindle 41, weighted arms, plug 44, pin 48, double armed lever 49, all applied thereto and constituting another unit 40 of the structure is then applied to the open side of the casing and bolted thereto with the other end of the crank shaft received in the bearing 21. The cover plate unit 24 with the governor adjusting screw 56 and spring 45 55 and cap 26 is then bolted on to the bearing ring 22. Before the cover plate unit is applied the throttle valve reach rod is inserted through the casing and attached to the arm 50, and the piston rod with piston attached 50 is inserted through and into the cylinder from its open end and said rod clamped upon the crank of the crank shaft.

The end of the exhaust valve operating lever 85 is then inserted through the opening 87 in the casing and its pivot pin 86 put in place.

The cylinder head with its various parts assembled thereon is then bolted on to the end of the cylinder, the nozzle 96 is bolted 60 on with the throttle valve in place therein, and the tank connection 95 attached thereto, and finally the exhaust connection 62 is applied, the drive pulley 19 is placed and the circulating water is supplied, and the engine 65 is ready to start up.

It is to be understood that many variations and changes in details might readily occur to persons skilled in the art and still fall within the spirit and scope of my invention. I do not desire, therefore, to be 70 limited or confined to the exact details shown and described.

But having now set forth the objects and nature of my invention and a construction embodying the principles thereof, what I 75 claim as new and useful and of my own invention is:—

1. In an internal combustion engine, a cylinder and piston, a crank shaft, a fly wheel, a governor mechanism and gearing driven 80 by the crank shaft to operate the same and a magneto, in combination with a casing having a chamber in which said crank shaft is journaled, said chamber also enclosing all of said parts. 85

2. In an internal combustion engine, a casing having an opening in one side thereof, a crank shaft, a bearing formed in the closed side of the casing to receive one end of said shaft, a bearing ring removably 90 bolted to the open side of said casing and having a bearing for the other end of said shaft, and a cover plate applied to said ring to form a closure for said casing.

3. In an internal combustion engine, a 95 casing having an opening in one side thereof, a crank shaft, a bearing formed in the closed side of the casing to receive one end of said shaft, a bearing ring removably bolted to the open side of said casing and having a bearing for the other end of said shaft, a cover plate applied to said ring to form a closure for said casing, said cover plate having an opening in line with the end of said shaft, and a cap for the opening in said cover plate. 100

4. In an internal combustion engine, a casing having an opening in one side thereof, a crank shaft, a bearing formed in the closed side of the casing to receive one end of said shaft, a bearing ring removably 110 bolted to the open side of said casing and having a bearing for the other end of said shaft, and a cover plate applied to said ring to form a closure for said casing, said cover plate having an opening disposed in line with said shaft. 115

5. In an internal combustion engine, a casing having an opening in one side thereof, a crank shaft, a bearing formed in the 120 closed side of the casing to receive one end of said shaft, a bearing ring applied to the open side of said casing and having a bearing for the other end of said shaft, a magneto mounted on said bearing, and a cover plate applied to said ring to form a closure for said casing. 125

6. In an internal combustion engine, a casing having an opening in one side thereof, a crank shaft, a bearing formed in the 130

- closed side of the casing to receive one end of said shaft, a bearing ring applied to the open side of said casing and having a bearing for the other end of said shaft, said bearing having a planed off surface to form a seating, a magneto mounted upon said seating, and geared to said shaft, and a cover plate adapted to be attached to said ring to form a closure for said casing.
- 10 7. In an explosive engine, a casing having an integral closed wall in one side thereof and an opening in the opposite side wall, said closed wall having a bearing therein, a crank shaft having one end journaled in
- 15 said bearing, a ring member having a bearing therein to form a journal for the other end of the shaft, said ring member removably secured upon the open side of said casing, and a fly wheel mounted on said
- 20 shaft and located within said casing.
8. In an explosive engine, a casing having an integral closed wall in one side thereof and an opening in the opposite side wall, said closed wall having a bearing therein, a crank shaft having one end journaled in
- 25 said bearing, a ring member having a bearing therein to form a journal for the other end of the shaft, said ring member adapted to be secured upon the open side of said
- 30 casing, a governor mechanism carried by said ring member and geared to said shaft, said governor mechanism being enclosed within said casing, and a cover plate for
- 35 said ring member.
9. In an explosive engine, a casing having an integral closed wall in one side thereof and an opening in the opposite side wall, said closed wall having a bearing therein, a crank shaft having one end journaled in
- 40 said bearing, a ring member having a bearing therein to form a journal for the other end of the shaft, said ring member removably secured upon the open side of said
- 45 casing, a cam gear journaled upon said ring member and geared to said shaft, and a cover plate for said ring member.
10. In an explosive engine, a casing having an integral closed wall in one side thereof and an opening in the opposite side wall, said closed wall having a bearing therein, a crank shaft having one end journaled in
- 50 said bearing, a ring member having a bearing therein to form a journal for the other end of the shaft, said ring member adapted to be secured upon the open side of said
- 55 casing, a governor mechanism carried by said ring member, a cam gear journaled upon said ring member and driven from said shaft, said cam gear being geared to
- 60 said governor mechanism.
11. In an explosive engine, a casing having an integral closed wall in one side thereof and an opening in the opposite side wall, said closed wall having a bearing therein, a crank shaft having one end journaled in
- 65
- said bearing, a ring member having a bearing therein to form a journal for the other end of the shaft, said ring member removably secured upon the open side of said casing, a stud mounted in said ring member, and a cam gear journaled upon said stud and geared to said shaft.
12. In an explosive engine, a casing having an integral closed wall in one side thereof and an opening in the opposite side wall, said closed wall having a bearing therein, a crank shaft having one end journaled in
- 70 said bearing, a ring member having a bearing therein to form a journal for the other end of the shaft, said ring member removably secured upon the open side of said casing, a gear journaled upon said ring member and formed with a cam at the hub thereof, said gear being driven from said shaft.
13. In an explosive engine, a cylinder and
- 80 casing integrally connected, a governor, fly wheel and magneto, said casing formed in one piece and arranged to enclose said parts and having an open side and means to close
- 85 said open side.
14. In an explosive engine, a cylinder and
- 90 piston, a crank shaft connected to said piston, and a fly wheel mounted on said shaft, in combination with a casing to enclose said cylinder, crank shaft and fly wheel, said casing having an integral side wall provided with a bearing to receive one end of said shaft, the side wall of said casing having an opening therein, and a removable member
- 95 detachably connected to the open side of
- 100 said casing and having a bearing to receive the other end of said shaft.
15. In an explosive engine, a cylinder and
- 105 piston and a crank shaft, in combination with an enclosing casing for these parts, said casing having an integral side wall, the opposite side of the casing having an opening, a bearing ring detachably mounted upon the open side of the casing, the respective ends of said shaft being journaled in bearings in
- 110 said integral side wall and in said bearing ring.
16. In an explosive engine, a casing having one side wall formed integrally therewith and having an opening in the opposite side wall, a bearing ring detachably connected to the open side of the casing, bearings formed in said integral side wall and in said bearing ring, and a crank shaft having its ends respectively journaled in said bearings.
17. In an explosive engine, a casing having one side wall formed integrally therewith and having an opening in the opposite side wall, a bearing ring detachably connected to the open side of the casing, and a magneto mounted on said bearing ring and disposed within said casing.
18. In an explosive engine, a casing having one side wall formed integrally therewith and having an opening in the opposite

side wall, a bearing ring detachably connected to the open side of the casing, a magnet mounted on said bearing ring and disposed within said casing, and a cover plate 5 detachably mounted on said bearing ring.

19. In an explosive engine, a casing having a closed side and an open side, a bearing ring detachably secured to the open side of the casing, a crank shaft journaled at its 10 ends in bearings formed in the closed side of the casing and in said bearing ring, respectively, a governor mechanism arranged within said casing, and including a rotatable spindle, said spindle journaled in a bearing 15 in said bearing ring and geared to said crank shaft, a rock shaft also journaled in a bearing in said bearing ring and having arms, one of said arms arranged to be rocked by said governor mechanism, and a throttle valve rod connected to the other of said arms.

20. In an explosive engine, a casing having a closed side and an open side, a bearing

ring detachably secured to the open side of the casing, a crank shaft journaled at its 20 ends in bearings formed in the closed side of the casing and in said bearing ring, respectively, a governor mechanism arranged within said casing, and including a rotatable spindle, said spindle journaled in a bearing 25 in said bearing ring and geared to said crank shaft, a rock shaft also journaled in a bearing in said bearing ring and having arms, one of said arms arranged to be rocked by said governor mechanism, and a throttle 30 valve rod connected to the other of said arms.

In testimony whereof I have hereunto set my hand on this 29th day of March, A. D. 1920.

MEYER J. GOLDBERG.
